Henry Dreyfuss, New York, N. Y., assignor to Hy-grade Sylvania Corporation, Salem, Mass., a corporation of Massachusetts

Application September 11, 1940, Serial No. 94,947

Term of patent 7 years

To all whom it may concern:

Be it known that I, Henry Dreyfuss, a citizen of the United States, residing at New York, in the county of New York and State of New York, have invented a new, original, and ornamental Design for a Fluorescent Lamp, of which the following is a specification, reference being had to the accompanying drawing, forming part thereof.

Figure 1 is a perspective view, as seen from above, of a fluorescent lamp showing my new design.

Figure 2 is a side elevational view of a fluorescent lamp.

Figure 3 is a top plan view of a fluorescent lamp.

I claim:

The ornamental design for a fluorescent lamp, as shown.

HENRY DREYFUSS.
